UNITED STATES PATENT OFFICE.

FREDERICK WILLIAM LANCHESTER, OF LONDON, ENGLAND.

FUEL-FEED VALVE AND VALVE-OPERATING MECHANISM FOR INTERNAL-COMBUSTION ENGINES.

1,274,059.

Specification of Letters Patent.

Patented July 30, 1918.

Application filed October 30, 1917. Serial No. 199,390.

To all whom it may concern:

Be it known that I, FREDERICK WILLIAM LANCHESTER, a subject of the King of Great Britain and Ireland, and residing at 41 5 Bedford Square, London, W. C. 1, England, have invented certain new and useful Improvements in Fuel-Feed Valves and Valve-Operating Mechanism for Internal-Combustion Engines, of which the following is 10 a specification.

The present invention relates to improvements in fuel feed valves for internal combustion engines and refers more especially to an improved type of valve and valve 15 operating mechanism for internal combustion engines of the high pressure self-ignition type.

In high pressure engines of the Diesel or self-ignition type as heretofore constructed 20 the fuel has been admitted by a timed cam-operated valve allowing the liquid fuel to pass under high pressure to a fine jet or jets giving admission to the combustion space. In some cases air under pressure is 25 admitted simultaneously with the liquid fuel or the latter is blown in by highly compressed air from a passage or recess into which it has been previously injected; in other cases the fuel is sprayed under its 30 own pressure.

The present invention relates to improvements in fuel valves and fuel valve gears of the type in which the valve is opened by impact, such type being more especially 35 applicable to engines in which auxiliary air is not employed. The volume of liquid fuel to be injected into the cylinder at each stroke is relatively very small; and such volume, when the flow takes place under constant 40 pressure, depends on three factors, viz., the difference between the pressures of the oil in the supply channels and of the pre-compressed air in the cylinder, (which affects the velocity of efflux of the oil), the effective 45 area of the valve opening, and the time during which the valve remains open. The velocity of efflux is necessarily great; with the usual type of cam-operated fuel valve the time during which the valve is held 50 open is relatively long, and therefore the effective area of opening must be kept very small. The usual type of fuel admission device is a needle valve. It has been proposed to use a needle valve held down on its 55 seat by spring pressure, and opened by the

impact of a striker released at the proper intervals by timing mechanism the impact of the striker being transmitted to the needle valve by means of a bell-crank lever. The impact effect of a hammer blow is however, more or less dissipated if transmitted through an elastic member like a bell-crank lever, and this type of construction is 60 avoided in the present invention.

In some cases a fuel measuring pump is 65 employed, the object being to measure off a definite volume of fuel to be discharged into the cylinder at each stroke of the engine piston. Owing, however, to the large volume of the passages from the fuel measuring pump to the point of discharge into the cylinder, as compared with the measured volume, the amount of oil delivered to the cylinder may vary considerably from 70 stroke to stroke, and the device fails to give 75 the desired result.

The present invention consists in opening the fuel valve by the direct impact of a suitably timed hammer or "tup" which strikes the valve stem or a piece rigidly fastened 80 thereto.

The invention also consists in closing the valve by means of the fuel pressure acting differentially on the plunger or valve stem, so that the valve under fuel pressure tends 85 to remain closed.

The invention further consists in an improved fuel valve arranged to open direct into the cylinder or combustion space, in which the lips of the valve and seat form 90 the injection nozzle.

The invention further consists of means, independent of the means for timing the hammer blow, for varying the effective impulse of the blow whereby the time during 95 which the valve remains open can be regulated as the load on the engine varies.

The invention also consists in combinations of the above devices.

Referring to the accompanying sheet of 100 illustrative drawings:—

Figure 1 is a section through a fuel valve and mounting constructed in accordance with the present invention; the plane of section includes both the axes of the valve 105 and fuel passage.

Fig. 2 is a section through a pneumatic device for operating the valve at the desired instant by the impact of a pneumatically impelled hammer or tup.

Fig. 3 represents diagrammatically a pneumatic pump and timing device suitable for actuating the pneumatic device aforesaid by means of which the hammer or tup is caused to deliver its blow.

In detail reference to the figures, in which like letters refer to like parts throughout, A¹ is the valve head of which the stem A² is securely attached to the ram or balance 10 plunger A³ of suitably larger diameter than the effective diameter of the valve seat. This plunger has formed on it a butt A⁴ adapted to be acted upon by impact in the manner hereinafter described. B¹ is the 15 valve box or mounting having a passage B² for the supply of liquid fuel admitted under appropriate pressure through a supply pipe B³ and port B⁴. A plug B⁵ may be provided to permit of cleaning the passage B² and to 20 allow at any time of trapped air being discharged in cases where the position of the valve is vertical as shown. A spring A⁵ is provided to retain the valve A¹ seated independently of the pressure force difference. 25 The valve unit A¹ A² A³ A⁴ is so constructed and connected as to constitute virtually one solid piece; in the example illustrated the valve stem is screwed into the butt the screw being pegged and grouted 30 with solder. The valve is permitted a small degree of movement only, the greatest possible opening being limited by the shoulder of the butt portion A⁴ making contact with the valve box or lug B¹. The valve unit is 35 actuated by the impact of a hammer or tup C¹ striking the valve butt A⁴, the said impact causing the valve to lift against the pressure on the differential area and the valve spring. The blow thus administered causes 40 the valve to jump, the period during which it thus remains open being very brief but nevertheless sufficient to permit of the injection of the fuel under the heavy pressure which is employed in order to spray or 45 atomize the charge. The tup or hammer C¹ is fitted within the cylinder D¹ and is raised into its topmost position by the spring C². Air pressure is admitted by a port D² at a pre-arranged point of the cycle an appropriate degree in advance of the required 50 fuel injection; the air admitted by D² acts on the tup C¹ to overcome the spring pressure and give the required blow. Both the timing of the air admission and the pressure used may be made variable and the means of 55 variation may be placed in the hands of the driver or attendant, or automatic control may be provided. The momentum of the blow may be varied by shortening or lengthening the stroke permitted to the tup by 60 means of a screwed stop D³ arranged to be screwed in or out for this purpose.

Whereas in engines in which the fuel valve is cam operated the time of opening 65 varies according to (inversely as) the speed

of revolution, with my invention the time the fuel valve remains open, and therefore the amount of fuel delivered to the combustion space at each stroke, is independent of the speed.

In the form of fuel valve described in the present specification the spraying is more effective than is the case with an ordinary needle valve. When the latter is employed the fuel passage terminates in the combustion space as a rose nozzle in which the fuel passes through a number of finely drilled passages. During the periods when the valve is not fully opened the fuel is withdrawn and the full fuel pressure is not admitted to the rose nozzle, the velocity of efflux is low and atomization is imperfect.

Having now described my invention, what I claim as new and desire to secure by Letters Patent is:—

1. An internal engine of the type described comprising an engine cylinder having an inlet port, and a fuel supply passage leading thereto, a normally closed valve controlling said inlet port having a valve stem, 90 a hammer normally retracted from said stem and arranged to operate on said valve stem, and means for actuating said hammer at the proper times to deliver a percussive blow to said stem.

2. An internal engine of the type described comprising an engine cylinder having an inlet port, and a fuel supply passage leading thereto, a normally closed valve controlling said inlet port having a valve stem, a 100 butt rigidly carried by said valve stem, a hammer yieldingly pressed away from said butt and arranged to operate on said butt, and means for actuating said hammer to give a percussive blow to said butt.

3. An internal combustion engine of the type specified comprising an engine cylinder having an inlet port and a fuel passage leading thereto, a normally closed valve controlling said port and arranged to open in 110 the direction of flow of the fuel, and having a suitable stem, a hammer, a spring normally pressing said hammer away from the stem arranged to act on said stem, and means for operating said hammer to deliver 115 a percussive blow to said stem.

4. An internal combustion engine of the type specified comprising an engine cylinder having an inlet port provided with a valve seat facing the combustion chamber, a valve 120 within the combustion space co-operating with said seat to form an injection nozzle, said valve having a suitable valve stem, means for holding said valve normally closed, a percussive hammer for acting on 125 said stem to open the valve, and means for operating said hammer.

5. An internal combustion engine of the type specified comprising an engine cylinder having an inlet passage and a valve seat, 130

an inwardly opening valve having a stem provided with a part of greater area working in said passage, means for conducting fuel under pressure to said inlet between the 5 valve and said part, and a percussive hammer for operating said valve.

6. An internal engine of the type described comprising an engine cylinder having an inlet port, and a fuel supply passage 10 leading thereto, a normally closed valve controlling said inlet port having a valve stem, a hammer arranged to operate on said valve stem, and means for actuating said hammer

at the proper times, and means for varying the stroke of the hammer.

7. An internal engine of the type described comprising an engine cylinder having an inlet port, and a fuel supply passage leading thereto, a normally closed valve controlling said inlet port having a valve stem, 15 a pneumatic percussive hammer arranged to operate on said valve stem, and means for actuating said hammer at the proper times,

In testimony whereof I have affixed my signature.

FREDERICK WILLIAM LANCHESTER.
